UNITED STATES PATENT OFFICE.

LEWIS T. CANFIELD, OF CHICAGO, ILLINOIS.

CAR-ROOF.

1,084,604.

Specification of Letters Patent.

Patented Jan. 20, 1914.

Application filed August 26, 1912. Serial No. 717,171.

To all whom it may concern:

Be it known that I, LEWIS T. CANFIELD, a citizen of the United States, and resident of Chicago, county of Cook, and State of Illinois, have invented certain new and useful Improvements in Car-Roofs, of which the following is a specification, and which are illustrated in the accompanying drawings, forming a part thereof.

10 The invention relates to roofs for cars, and is especially adapted for use in connection with freight cars.

The object of the invention is to provide a roof which is made entirely of sheet metal 15 and in which the framing ordinarily used, consisting of a rigid pole, carlines and purlins, may be dispensed with.

The further object is to provide a roof which shall be rigid.

20 One form of construction exemplifying the invention is fully hereinafter described and is illustrated in the accompanying drawings, in which—

Figure 1 is a detail plan view of the roof, 25 partly broken away; Fig. 2 is a cross sectional detail, on the line 2—2 of Fig. 1; Fig. 3 is a detail longitudinal section of the roof, taken a little to one side of the ridge thereof; and Fig. 4 is a detail of one of the plates 30 of which the roof is composed.

The roof is formed of a plurality of sheet metal plates, each plate extending from the ridge of the roof to the eaves of the car and having its edges folded or flanged downwardly, adjacent flanges of the several plates 45 lying side by side and being secured together, the eave flanges being folded down over the outer surface of an eave plate, and the flanges at the ends of the car being folded down upon an end plate.

The roof is especially adapted for use in connection with metal cars, as the framing of such cars is itself rigid and not subject to distortion under heavy loads, as are wood 45 cars.

Box cars made of metal are usually provided with uprights, as 10, which may be of steel rolled to any desired form, the siding 50 11 being secured to the inner faces of these uprights.

The improved roof is formed of plates, such as 12, 13, 14, 15. Each plate has its margins folded downward to form flanges, as 16, 17, 18, 19. The flanges 16, which are 55 at the ridge of the roof, are inclined back-

wardly, so that they assume a vertical position when the plates are in the inclined position they assume in the formation of a pitched roof, the ridge flanges of the inclined plates, as 14, 15, lying side by side 60 and being secured together, as by means of rivets 20. The eave flange of each plate extends downwardly outside of an eave plate 21 secured to the outer faces of the uprights 10 and preferably extending from end to end 65 of the car, the flanges 18 being secured to this eave plate, as by means of rivets 22. The side flanges of adjacent plates lie side by side and are secured together, as by means of rivets 23. The lower ends of these side 70 flanges may be cut away as necessary to fit within the eave plate 21, as shown in Fig. 2.

The outer side flanges of the plates, as 12, 13, at the end of the car, are folded down over the outer face of the car end, as shown 75 in Fig. 3, and are secured thereto, as by the rivets 24.

The cross seams in the roof at the juncture of the several plates are covered by plates 25 extending from side to side of the car and 80 being lapped down over the depending flanges 18 of the roof plates, and are secured to the roof plates, as by rivets 26. The ridge seam of the roof is similarly covered by a plate 27 extending from end to end of the 85 car and lapping downwardly over the depending flanges 19 of the end plates, and being secured to the various plates, as by rivets 28.

In a roof thus formed the ridge flanges 90 16 supply the place of a ridge pole, and the side flanges of the plates provide the strength heretofore secured by the use of carlines. It becomes unnecessary, therefore, to provide a framing for supporting the roof, and the latter will be rigid and inflexible and will contribute to the strength of the entire structure of the car.

A running board 29 may be mounted upon brackets, as 30, secured to the ridge of the 100 roof by means of rivets or bolts.

The roof while being shown as made of flat plates may be given any desired cross-sectional configuration.

I claim as my invention:

1. A car roof formed of a plurality of sheet metal plates, each plate extending from the ridge of the roof to the eaves and having a downstanding continuous flange along its sides and its end at the ridge of 110

the roof, the flanges of adjacent plates being in face to face contact and rigidly secured together.

2. A car roof formed of a plurality of sheet metal plates, each plate extending from the ridge of the roof to the eaves and having a downstanding continuous flange along its sides and its end at the ridge of the roof, the flanges of adjacent plates being in face to

face contact and rigidly secured together, 10 and plates covering the joints at the meeting edge of adjacent plates and being riveted to each of such plates.

LEWIS T. CANFIELD.
